CENTRIFUGAL SEPARATOR

Clyde E. Bannister, Bartlesville, Okla.

Application February 27, 1940, Serial No. 321,098

8 Claims. (Cl. 233—21)

This invention relates to centrifugal separators and especially to devices adapted to separate a finely divided and suspended solid from a liquid.

Its chief objects are to provide an improved apparatus for performing the separating operation while the liquid is "in transit," so to speak, as in the case of drilling fluid being drawn from the slush pit by a pump in the drilling of deep wells such as oil wells; to provide for separating the materials while causing them to move upward, as in the case of the drilling fluid just mentioned; to provide simplicity of construction and of operation; and to provide economy of construction and of operation.

Of the accompanying drawings:

Fig. 1 is a vertical axial section, with inner members shown in elevation, of an apparatus embodying my invention in its preferred form.

Fig. 2 is a section on line 2—2 of Fig. 1.

Fig. 3 is a section on line 3—3 of Fig. 1.

Fig. 4 is a fragmentary elevation of the lower end portion of the apparatus.

Fig. 5 is a vertical middle section of a modification.

Referring to the drawings, 10 is a slush pit such as is employed in the drilling of oil wells, the liquid therein having its level at 11. The suction line of a pump is shown at 12, supported by means such as a cable 13, and the terminal, vertical pipe section of the suction line has mounted upon its lower end a stationary suction nozzle 14 formed with intake holes 15, 15 and preferably of downwardly tapered form as shown and provided with a bottom end-closure 16 (Figs. 2 and 3).

At the upper end of the suction nozzle 14 its edge face, around the pipe section 12, provides a shoulder serving as the support for the lower race of a radial-and-thrust bearing 17 which rotatably supports a rotor-head member 18 which also is provided with a vertically extensive radial bearing 19 interposed between it and the pipe-section 12. Screwed upon a reduced upper end portion of the rotor-head member 18 is a belt-pulley member 20 adapted to be rapidly rotated by a belt 21 for rotating the rotor-head 18 and a centrifugal separator device which is threaded upon it at 22.

This separator device comprises a shell portion 23 which in spaced relation surrounds the suction nozzle 14 and in the region of the latter preferably is tapered downwardly at an angle of taper such that the flow capacity of the annular space between them is about the same at all elevations excepting allowance for fluid leaving the

annular space and entering the suction nozzle at various elevations in the upward impelling of the fluid in the annular space.

In this annular space are two helico-spiral impeller vanes or ramps 24, 24 which are in the relation of the threads of a double-threaded screw and which are secured throughout their length, at their outer margins, to the shell member 23 and at their inner margins have a preferably sealing fit against the stationary suction nozzle 14. Gaskets 25, 25 may be set in grooves formed in the inner edge faces of the ramps, if found necessary or desirable under any particular set of speed and other conditions, although ordinarily a little leakage at that position is not harmful.

At their lower ends the ramps 24 terminate at 24^a, 24^a, at diametrically opposite positions for balance of torque and of bearing load, and below 20 the lowermost half-turn of each ramp the casing or shell member 23 is cut away as at 26 to permit liquid to be present in front of the mouth of the helico-spiral channels defined by the nozzle, the shell, and the ramps, for a Pitot effect as an 25 assistance to the centrifugal effect for causing the ramps to lift the liquid to their upper ends and there discharge it into the annular space defined by the shell, and the upper end portion of the shell is formed with a plurality of discharge 30 openings 27, 27 for the outflow from the shell of liquid heavily laden with the solid particles by reason of the centrifugal separation occurring in the upward flow of the liquid.

Preferably a conical apron 28, sloping downwardly outwardly, is mounted upon the shell member 23 just below the outlet openings 27, for throwing the heavily laden liquid to such distance from the intake nozzle that the solids will largely settle out of it instead of being again 40 drawn into the suction nozzle.

In the operation of the apparatus, the rotor comprising the shell 23 and the ramps 24 being rapidly rotated in the direction of the arrow in Fig. 3 and suction being applied to the pipe 12 45 and nozzle 14 by the pump, the sand laden water, for example, is caused to flow upward between the vanes or ramps 24 both by the Pitot effect of the open mouths of the inter-vane spaces and by the centrifugal-pump effect resulting from the 50 fact that the outlets 27 are farther from the axis of rotation than are the said mouths of the inter-vane spaces.

It is desirable that the several dimensions of the parts of the apparatus be so correlated with each other and with the speed of rotation that

throughout the height of the vanes or ramps there will be a lag, which is to say a relative backward flow, of the liquid in relation to the ramps 24 and the shell member 23, the liquid not attaining the full speed of the rotor even at the tops of the vanes or ramps, so that there will be a washing upward on the ramps, to the outlets 27, of the sand concentrated in the outer region of the inter-vane spaces.

Preferably the lower end portion of the suction nozzle 14 is imperforate to a sufficient height to assure centrifuging of the liquid before it reaches the elevation of any of the intake ports 15, so that only water made substantially free from sand by the centrifuging will be drawn into the nozzle.

In order that the highest intake ports 15 of the nozzle may not be opened to the atmosphere by reason of centrifugal force of the water causing it to bank up in the inter-vane spaces, thus leaving the nozzle, the outlet ports 27 can be made sufficiently small to assure that all of the space between the nozzle and the shell will be at all times full of water, but, rather than to have such impedance of flow, it is preferable to assure contact of the water with the nozzle throughout the region of the intake apertures primarily by so proportioning the parts that the flow capacity at all positions will be equal excepting an allowance for water taken into the nozzle at positions lower than such position as may be under consideration, so that the inter-vane spaces will be full of water throughout their cross-sectional areas and entirely to the tops of the vanes.

In the modification shown in Fig. 5, the casing 23^a is non-rotating, being fixedly supported from its upper end, where it is secured as by screws 30, 30 to a plate 21 which is clamped between nuts 32, 32 screwed upon the suction pipe 12^a. The helico-spiral vanes 24^a, 24^a, for rotation within the stationary casing 23^a, are secured to respective brackets or arms 33, 33 preferably of stream-line cross-sectional form, by means such as the screw 34, and these arms are secured at their upper ends, as by means of screws 35, 35, to a hub-member 36 which is journaled upon the suction pipe 12^a by means of radial bearings 19^a and a radial-and-thrust bearing 17^a, and is formed at an intermediate portion with an annular flange 37 which is grooved for the reception of a driving belt 21^a.

The casing 23^a, in its upper portion, is formed with large holes 23^b, 23^b, for access of water to the forwardly-facing mouths of the inter-vane spaces, the device being suspended so that at least the lower portions of such holes are below the water level.

In this embodiment the hub-member 36 and with it the vanes 24^a are driven in such direction that the vanes urge the water-and-sand mixture downward while centrifuging it, and downward movement of sand, concentrated against and close to the outer casing 23^a is somewhat retarded as to its rotary movement by frictional resistance with relation to the casing, and this enhances the effect of the vanes in urging it downward and expelling it at their lower ends, the principle involved being somewhat similar to that by which a sausage machine, by coaction of the screw and of the inner face of the cylinder of the machine, forces the sausage meat through the rotating apertured cutter discs. I do not wholly limit my claims to downward forcing of the sand in this way.

Fig. 5 shows the suction nozzle 14^a and the cas-

ing 23^a as being downwardly flared, for centrifugal-pump effect, but this flare is less important in this embodiment, with gravity helping to move the sand downward, than it is in the upwardly-impelling embodiment shown in Fig. 1.

In this embodiment of Fig. 5, as well as in that of Fig. 1, the flow-space between the vanes 24^a, 24^a preferably is of decreasing cross-section toward the delivery end of the device, to compensate for fluid drawn into the suction nozzle at different positions along its length, so that excessively low pressure of the fluid against the suction nozzle, as an incident of centrifugal force, is avoided.

The vanes 24^a may be secured at their inner margins to a very open, frusto-conical skeleton 38 to prevent them from being excessively sprung by centrifugal force or by the resistance of the fluid.

It will be manifest that in the operation of this embodiment shown in Fig. 5 the intake water is drawn from the upper part of the body of water, where the sand or silt may have settled out previously, by gravity, to some extent, and that the discharge of water heavily laden with sand is nearer to the bottom of the pit, to which the discharged sand can settle, and it is somewhat distributed by centrifugal force as it leaves the lower end of the centrifuging device.

Various other modifications are possible within the scope of the invention as defined by the appended claims.

I claim:

1. Centrifuging apparatus comprising a fluid-intake nozzle leading to an outlet for the lighter one of the substances separated, a non-rotating casing surrounding the same and having an outlet for the other substance, a member mounted between the two for rotation about the nozzle and having a face disposed in screw-thread relation to the axis of rotation and thus adapted in such rotation to impel axially of the assembly a fluid occupying the space between the nozzle and the casing, and means for so rotating said member.

2. Centrifuging apparatus comprising a non-rotating fluid-intake nozzle leading to an outlet for the lighter one of the substances separated, a non-rotating casing surrounding the same and having an outlet for the other substance, a member mounted between the two for rotation about the nozzle and having a face disposed in screw-thread relation to the axis of rotation and thus adapted in such rotation to impel axially of the assembly a fluid occupying the space between the nozzle and the casing, and means for so rotating said member.

3. Centrifuging apparatus comprising a fluid-intake nozzle leading to an outlet for the lighter one of the substances separated, a casing surrounding the same and having an outlet for the other substance, a member mounted between the two for rotation about the nozzle and having a face having screw-thread relation to the axis of rotation and thus adapted in such rotation to impel axially of the assembly a fluid occupying the space between the nozzle and the casing, and means for so rotating said member, the said face being inclined in such direction as to impel the fluid downward.

4. Centrifuging apparatus comprising a non-rotating suction pipe, a fluid-intake nozzle mounted thereon, means surrounding said nozzle for centrifuging a liquid passing therewith, and means for supporting the assembly with the centrifuging means and the intake portion of the

75

nozzle submerged in a surrounding body of liquid, said centrifuging means comprising a drum having an inlet opening and rotatable conveying means communicating with said inlet opening and constructed and arranged to receive liquid from said surrounding body of liquid and convey it along said drum to said suction nozzle.

5. Centrifuging apparatus comprising a suction pipe, a fluid-intake nozzle mounted thereon and formed with radially-opening intake apertures, means surrounding said nozzle for centrifuging a liquid passing thereinto, and means for supporting the assembly with the centrifuging means and the intake portion of the nozzle submerged in a surrounding body of liquid, the centrifuging means comprising structure which with the nozzle defines a helical flow passage in communication with said apertures.

6. Centrifuging apparatus comprising a non-rotating suction pipe, a non-rotating nozzle mounted thereon and formed with radially-opening intake apertures, means surrounding said nozzle for centrifuging a liquid passing thereinto, and means for supporting the assembly with the centrifuging means and the intake portion of the nozzle submerged in a surrounding body of liquid, the centrifuging means comprising structure which with the nozzle defines a helical flow passage in communication with said apertures.

7. Centrifuging apparatus comprising a suction pipe, a fluid-intake nozzle mounted thereon and formed with radially-opening intake apertures, means surrounding said nozzle for centrifuging a liquid passing thereinto, and means for supporting the assembly with the centrifuging means and the intake portion of the nozzle submerged in a surrounding body of liquid, the nozzle and the centrifuging means defining a helical flow passage in communication with said apertures and having a fluid receiving mouth which is forwardly facing with relation to the direction of rotation of the centrifuging means.

8. Centrifuging apparatus comprising a suction pipe, a fluid-intake nozzle mounted thereon and formed with radially-opening intake apertures, means surrounding said nozzle for centrifuging a liquid passing thereinto, and means for supporting the assembly with the centrifuging means and the intake portion of the nozzle submerged in a surrounding body of liquid, the nozzle and the centrifuging means defining two helical flow passages in communication with said apertures and having respective diametrically opposite fluid receiving mouths which are forwardly facing with relation to the direction of rotation of the centrifuging means.
